1

This invention relates to rayon spinning machinery.

In the production of artificial threads by the box-spinning process, a thread-forming solution such as viscose is extruded through a jet into a coagulating medium and the filaments so formed are withdrawn by means of godets and are then passed by means of a reciprocating guide into a rotating spinning box in which a cake of thread is formed. The godets hitherto employed have usually been corrugated so that the ridges and the grooves between successive ridges have approximately the same width. With high spinning speeds, that is to say speeds of the order of 90 metres per minute or more, and using conventional godets, it is not always easy for the operative to set-up the thread, that is to pass the thread from the godet into the spinning box via the reciprocating funnel or other guide used to lay the thread in the box. The cohesion between the thread and the conventional godet at high speeds is usually so great that in the short time interval available between taking the thread from the godet and the initiation of the pull of the box to start the spinning process the thread licks under the godet and the attempted setting-up fails.

The object of the present invention is to provide an improved design of godet or equivalent thread take-up and delivery device which facilitates the setting-up of the thread at high speeds.

We have found that by suitably reducing the width of the thread-supporting surfaces and also by increasing the distance separating such surfaces, a godet or equivalent device is obtained which permits easy setting up at speeds of the order of 100 metres per minute or higher, for example up to 125 metres per minute.

Accordingly the present invention consists of a rotatable thread take-up and delivery device comprising at least twenty thread-supporting bars arranged substantially uniformly around and equidistant from the centre of rotation of the device, the thread-supporting surface of each bar being not greater than 0.1 of an inch in width at the point at which the thread leaves the device and the pitch of the bars, that is the distance between the centres of successive bars, being from 0.5 of an inch to 2 inches.

The take-up and delivery device according to the invention is preferably a godet but the device may be formed by a number of circumferential bars carried by a spider mounted on the driving shaft of the device.

The bars of the device are preferably of uniform width along their whole length but if de-

sired they may be wider than 0.1 of an inch at the take-up end, provided that the width is reduced to below 0.1 of an inch at the discharge point. The number of bars at the take-up end may also be different from the number of bars at the discharge end.

The invention also includes a process for the production of rayon thread in cake form by extruding a thread-forming solution through a jet into a coagulant and passing the resulting filaments to such a thread take-up and delivery device and then to a rotating spinning box at a speed of at least 90 metres per minute by means of a reciprocating funnel.

15 The godet or equivalent take-up and delivery device according to the invention effects a substantial reduction in the force necessary to cause the wet thread to leave its surface. The device may therefore also be used in the spinning of 20 thick cakes of light denier filament threads, for example of 60 filament/60 denier threads, without the premature breakdown which often occurs when the centrifugal pull from the rotating box falls to a low value towards the end of the 25 required collecting period. For example when spinning 60 filament/60 denier threads and using a conventional godet the collecting period for the cake is usually of the order of 15 to 16 hours whereas using godets according to the invention, collecting times of 19 hours or more may be used.

30 The thread take-up and delivery device according to the invention may be used with advantage with the spinning machines described in the specifications of copending applications 35 Serial Nos. 255,388, filed November 8, 1951, and 263,568, filed December 27, 1951, now Patents Nos. 2,633,693 and 2,633,694, respectively.

The present invention is illustrated by way of example in the accompanying diagrammatic drawings in which

40 Figure 1 is a view of a box-spinning machine incorporating a godet according to the invention,

Figure 2 is an end view of the godet according to the invention as shown in Figure 1, and

45 Figure 3 is a plan view of part only of the godet shown in Figure 2, on a larger scale.

Referring to Figure 1, viscose is extruded through a jet 1 into a coagulant bath 2 to form a thread 3 which is withdrawn from the bath 2 and 50 passed to a godet 4 of conventional design. The thread 3 is lapped first round the godet 4 by means of guide 5, then round a godet 6, constructed in accordance with the invention, and then passed directly to a rapidly-rotating box 7 in which it is laid by a reciprocating funnel 8.

Referring to Figures 2 and 3, the godet 6 is provided with a conventional flange 9 and has thirty-six circumferential bars 10 separated by thirty-six grooves 11. In one specific form of godet, the width of each bar 10 at its tip is 0.05 inch, the height of each bar is approximately $\frac{1}{8}$ inch and the overall diameter of the godet is $6\frac{3}{4}$ inches; the pitch of the bars in this specific godet is 0.59 inch and the width of the grooves 11 is 0.54 inch. The godet is conveniently about 3 inches long.

The application of this specific form of godet to high speed spinning of viscose and to the spinning of light denier filament threads is illustrated in the following examples. Percentages 15 are by weight.

Example 1

Viscose, containing 7.5 per cent of cellulose and 6.0 per cent of caustic soda, and aged to a salt point of 5.5, was extruded through a jet having 18 holes each of 3 thousandths of an inch diameter into a coagulant bath at 60° centigrade to form a 75 denier thread. The coagulant bath contained 10 per cent of sulphuric acid, 19 per cent of sodium sulphate and 1 per cent of zinc sulphate. After passing through the bath for about 10 inches, the thread was withdrawn from the bath at a speed of 80 metres per minute by means of a godet of conventional design. The thread was lapped round the conventional godet two and a half times and was then passed at a speed of 100 metres per minute to the godet described above having 36 teeth $\frac{1}{20}$ of an inch wide, the thread being lapped round this godet also two and a half times. The thread was then collected by means of a reciprocating glass funnel in a box of $6\frac{1}{2}$ inches diameter and rotating at 7,000 revolutions per minute. When spinning under these conditions, it was found that with the godet according to the invention a skilled operative experienced no difficulty in setting up the thread, whereas when the godet according to the invention was replaced by a conventional godet, the same operative experienced considerable difficulty in setting up and on an average only succeeded in setting up once in every four attempts.

Example 2

Viscose containing 7.5 per cent of cellulose, 6.0 per cent of caustic soda and aged to a salt point of 5.5, was extruded through a jet having 60 holes, each having a diameter of $2\frac{1}{2}$ thousandths of an inch, into a coagulating bath at 60° centigrade containing 9 per cent of sulphuric acid, 20 per cent of sodium sulphate and 1 per cent of zinc sulphate. After passing through the bath for a distance of 4 inches, the thread was withdrawn at a speed of 50 metres per minute by means of a conventional godet and passed at a speed of 62 metres per minute to a second godet as described above having a diameter of $6\frac{3}{4}$ inches and provided with 36 teeth each $\frac{1}{20}$ of an inch wide. The thread, of 60 denier, was passed from the second godet by means of a reciprocating funnel 9 inches long having four internal constrictions each 0.12 inch in diameter, and an orifice of 0.10 inch in diameter to a rotating centrifugal box 6 inches in diameter and rotating at 7,000 revolutions per minute. Under these

conditions, spinning breakdown occurred after $19\frac{1}{4}$ hours. The cake so produced was sufficiently thick in its walls to stand up to the pressure of a standard cake-washing machine.

6 A similar experiment in which the godet according to the invention was replaced by one of conventional design broke down by reason of insufficient pull at the godet after $15\frac{1}{2}$ hours. The cake walls were not sufficiently thick to ensure 10 perfect pressure washing and a cake of inferior quality was obtained.

The marked advantage in using the godet according to the invention may be judged by the following results obtained on a machine having 10 spinning ends similar to those described in Example 2, the machine being run continuously for one month.

Percentage failures in the cake washing process

20	With the conventional second godet	15
	With the novel second godet	0.5

During this run, spinning times of 18 hours were used with the novel godet, without any premature breakdown occurring, while, with the conventional godet, only 45 per cent of the cakes achieved the normal 16 hours spinning time. With the other 55 per cent, spinning broke down at times varying from 14-16 hours.

25 The godet used in the above examples may be replaced by a godet having an overall diameter of 7 inches and having 40 bars on its circumference, each bar being 0.05 inch in width and the pitch of the bars being 0.55 inch.

30 What we claim is:

35 1. A godet for high speed spinning into a rotating spinning box having thirty-six to forty thread-supporting bars arranged substantially uniformly around and equidistant from the centre of rotation of the godet, the width of the thread-supporting surface of each bar being 0.05 of an inch and the pitch of the bars being from about 0.55 to about 0.59 inch, whereby licking under of the yarn during setting up is avoided.

40 2. A godet for high speed spinning into a rotating spinning box having forty thread-supporting bars arranged substantially uniformly around and equidistant from the centre of rotation of the godet, the width of the thread-supporting surface of each bar being 0.05 of an inch and the pitch of the bars being .055 inch, whereby licking under of the yarn during setting up is avoided.

45 3. A godet for high speed spinning into a rotating spinning box, having thirty-six thread-supporting bars arranged substantially uniformly around and equidistant from the centre of rotation of the godet, the width of the thread-supporting surface of each bar being 0.05 of an inch and the pitch of the bars being about 0.59 inch, whereby licking under of the yarn during setting up is avoided.
